US00D667108S

(12) **United States Design Patent**
Mottahed

(10) **Patent No.:** **US D667,108 S**
(45) **Date of Patent:** **** Sep. 11, 2012**

(54) **SYRINGE PLUNGER ROD**

(75) Inventor: **Behzad Mottahed**, Upper Montclair, NJ
(US)

(73) Assignee: **Becton, Dickinson and Company**,
Franklin Lakes, NJ (US)

(**) Term: **14 Years**

(21) Appl. No.: **29/405,691**

(22) Filed: **Nov. 4, 2011**

(51) LOC (9) Cl. **24-02**

(52) U.S. Cl. **D24/130**

(58) Field of Classification Search **D24/112,**
D24/127, 130; 604/218, 232, 224, 228, 110,
604/195; 222/390

See application file for complete search history.

(57) **CLAIM**

The ornamental designs for a syringe plunger rod, substantially as shown and described.

DESCRIPTION

FIG. 1 is a top right rear perspective view of a syringe plunger rod;

FIG. 2 is a right view of a syringe plunger rod;

FIG. 3 is a left view of a syringe plunger rod;

FIG. 4 is a top view of a syringe plunger rod;

FIG. 5 is a bottom view of a syringe plunger rod;

FIG. 6 is a back view of a syringe plunger rod;

FIG. 7 is a front view of a syringe plunger rod;

FIG. 8 is a top right rear perspective view of a second embodiment of a syringe plunger rod;

FIG. 9 is a right view of FIG. 8;

FIG. 10 is a left view of FIG. 8;

FIG. 11 is a top view of FIG. 8;

FIG. 12 is a bottom view of FIG. 8;

FIG. 13 is a back view of FIG. 8; and,

FIG. 14 is a front view of FIG. 8.

The broken line showing in FIGS. 1-7 is for the purpose of illustrating portions of the article and form no part of the claimed design.

1 Claim, 8 Drawing Sheets
